F. OBERST

TONE ARM

Filed June 12, 1919

Fig. 2

Inventor
Frank Oberst
by Jacob Schechter
Attorney

UNITED STATES PATENT OFFICE.

FRANK OBERST, OF GLENDALE, NEW YORK, ASSIGNOR TO SONORA PHONOGRAPH CORPORATION, A CORPORATION OF NEW YORK.

TONE ARM.

Application filed June 12, 1919. Serial No. 303,614.

To all whom it may concern:

Be it known that I, FRANK OBERST, a subject of the Kingdom of Rumania, and residing at Glendale, in the borough of

5 Queens, county of Queens, and State of New York, have invented a certain new and useful Improvement in Tone Arms, of which the following is a specification.

My invention relates to tone-arms for 10 talking machines, and has for its objects to provide a tone-arm of fibrous material, having a joint whereby the arm may be lowered to engage the stylus with the record disc, and whereby the arm may be elevated 15 in order that the stylus will be accessible for insertion or removal.

A further object is to produce a tone-arm of the character described, in which the sound passage will be unobstructed.

20 A still further object is to provide means for locking the arm in inoperative position by devices which will be entirely disengaged when the arm is in operative position, whereby rattling and other objectionable 25 sounds will be obviated.

A further object of the invention is to provide means of the character herein described, simple in construction, thoroughly reliable and efficient in its purpose, positive in operation and inexpensive to manufacture.

30 With these and other objects in view to be more fully set forth hereinafter, the invention consists in the novel construction, combination of elements, and arrangement of parts which will be exemplified in the construction hereinafter described in the specification and illustrated in the accompanying drawings considered together or separately.

40 The inventive idea involved is capable of receiving a variety of mechanical expressions, one of which for the purpose of illustrating the invention, is shown in the accompanying drawings.

45 The invention will be first described in connection with the accompanying drawings illustrating one embodiment of my invention, wherein similar reference characters are used to designate corresponding parts throughout the several views, and then more specifically defined and indicated in the appended claims.

In the drawings:—

50 Fig. 1 is a longitudinal section of a tone-arm embodying my invention; and

Fig. 2 is a bottom plan view of the movable element of the arm and a co-operating device carried by the stationary member of the arm.

In carrying out my invention, I provide a 60 stationary sound post 1 which communicates with the horn or amplifier of a talking machine. The tubular 1, composed of wood or other fibrous material, is secured to the top of a motor board 2 to the under side of 65 which a motor (not shown) is secured. The motor is adapted to rotate the usual turntable 3 which carries a record 4.

Fitted within the enlarged spherical free 70 extremity of the post 1 is a metallic sleeve 5 which preferably engages an enlargement of the bore of the post by friction. Within the sleeve 5 and carried on vertical pivots 6 is a spherical gimbal ring 7 in which is pivoted on horizontal pivots 8 a second spherical gimbal ring 9. The ring 9 is an enlargement 75 of a sleeve 10 which is fitted in the bore of a movable tone-arm section 11.

The section 11 is composed of wood or 80 other fibrous material, and its inner end is provided with a spherical cup 12 adapted to overlap and preferably engage within an annular recess 13 in the enlarged free end of the post 1. The section 11 is therefore 85 capable of universal movement relatively to the post 1. Carried at the free extremity of the section 11 is a tubular element 14 which 90 carries a sound-box or reproducer 15 of any preferred type. Within the bore of the section 11 is a thimble 16 carrying a pair of oppositely disposed pins 17 which engage 95 curved slots 18 in a sleeve 18^a carried by the element 14, whereby the section and element may be locked together by an ordinary bayonet joint.

The vertically pivoted and horizontally 100 swinging gimbal ring 7 is provided with an outwardly projecting lug 19 to which is secured an arm 19^a to the lower end of which is pivotally secured a finger 20 adapted to engage and operate an element of an automatic stop mechanism, not shown.

In the lower rim of the cup 12 is a slot 21, and fixed within the slot is a U shaped 105 spring member 22, the legs of which project beyond the end of the slot. The inner side of each leg is provided with a button or pin 23 adapted to engage the arm 19^a when the section 11 is raised, as shown in full lines in Fig. 1.

The operation is as follows:—

When the tone-arm proper is in the operative position, as shown in Fig. 2, and in broken lines in Fig. 1, the needle or stylus 5 will rest within the record groove and be held therein by the weight of the tone-arm. The legs of the spring will straddle the arm 19^a, and said legs and the buttons carried thereby will be out of contact with 10 and beyond said arm, and during the playing of the record the section 11 will not engage any portion of the post 1 except the pivots of the gimbal rings.

When the section 11 is swung upward to 15 permit of changing the stylus, the buttons 23 will engage one side of the arm 19, spread the legs of the spring 22, and as the section reaches its ultimate height and released the buttons will engage the opposite side of the 20 arm, as shown in full lines in Fig. 1, and the section thus retained in raised position.

There are no springs, catches, latches, 25 pivots, rods or the like within the bore of the tone-arm, and the sound passage is at all times free and unobstructed.

In accordance with the provisions of the patent statute, I have described the principle of my invention, together with the apparatus which I now consider to represent 30 the best embodiment thereof, but I desire it understood that my invention is not limited to the particular form of apparatus herein shown and described, as it is obvious that the particular embodiment herein shown and described is only illustrative of my invention, and that other means can be employed to obtain these objects and accomplish these results, without departing 35 from the spirit of my invention.

40 Having now described my invention, what I claim and desire to secure by Letters Patent is:

1. A tone-arm, comprising a stationary 45 tubular post member terminating in an enlarged end having an annular spherical recess therein, a tubular movable member having an enlarged spherical cup-shaped end adapted to enter the spherical recess in the end of the post member, and a gimbal joint comprising independent members 50 fixed in the bores of and connecting said tone-arm members at the enlarged ends thereof and concealed by the overlapping ends of said tone-arm members and permitting a horizontal and vertical swinging 55 movement of said movable tone-arm member.

2. A tone-arm, comprising a stationary 60 tubular post member having an enlarged spherical end, a tubular movable member having an enlarged spherical cup-shaped end overlapping the enlarged spherical end

of the post member and provided with a slot in its lower rim portion, a gimbal joint for connecting said members and comprising a horizontally swinging portion fixed in the bore of the post member, and a vertically swinging portion fixed in the bore of the movable member, an arm depending from and carried by the horizontally swinging portion of the gimbal joint and in alinement with the slot in the cup-shaped end of the movable member, and a spring fixed in said slot and carried by the movable member and provided with a stop or lug adapted to engage said arm to support the movable member of the tone arm in an elevated or inoperative position and to be yieldingly disengaged from said arm to permit the movable member to assume its operative position.

3. A tone-arm, comprising a stationary tubular post member, a tubular movable member having a slot at its inner end, a gimbal joint for connecting said members and comprising a horizontally swinging portion fixed in the bore of the post member, and a vertically swinging portion fixed in the bore of the movable member, an arm depending from and carried by the horizontally swinging portion of the gimbal joint and in alinement with the slot in the end of the movable member, and a U-shaped spring fixed in said slot and straddling said arm and provided with stops or lugs adapted to engage said arm to support the movable member in elevated or inoperative position and to be yieldingly disengaged from said arm to permit the movable member to assume its operative position.

4. A tone-arm, comprising a stationary tubular post member, a tubular movable member, a gimbal joint for connecting said members and comprising a horizontally swinging portion fixed to the post member, and a vertically swinging portion fixed to the movable member, an arm depending from and carried by the horizontally swinging portion of the gimbal joint, and a U-shaped spring fixed to the vertically movable member of the tone-arm and straddling said arm and provided with stops or lugs adapted to engage said arm to support the movable member in elevated or inoperative position and to be yieldingly disengaged from said arm to permit the movable member to assume its operative position.

This specification signed and witnessed this 6th day of June, 1919.

FRANK OBERST.
